UNITED STATES PATENT OFFICE.

OSCAR C. DAVIS, OF BROCKTON, MASSACHUSETTS, ASSIGNOR OF ONE-HALF TO GEORGE E. KEITH, OF BROCKTON, MASSACHUSETTS.

SHOE.

1,129,649.

Specification of Letters Patent. Patented Feb. 23, 1915.

Application filed October 8, 1914. Serial No. 865,657.

To all whom it may concern:

Be it known that I, OSCAR C. DAVIS, a citizen of the United States, and resident of Brockton, in the county of Plymouth and State of Massachusetts, have invented certain new and useful Improvements in Shoes, of which the following is a specification.

This invention relates chiefly to the uppers of welted shoes, and has for its object to enable the quantity of leather necessary for such uppers to be reduced to the minimum with a corresponding reduction in the cost of manufacture, it being a well known fact that the cost of upper leather has materially increased and is constantly increasing.

My invention is embodied in a shoe upper comprising a body portion of leather and an edge portion composed of a relatively narrow strip of practically inextensible woven fabric of substantial tensile strength and adapted to be engaged by instrumentalities employed in pulling over the upper in the operation of lasting, the said strip constituting a pulling-over extension, which is the one part of the upper that is engaged by the pulling-over instrumentalities during the lasting operation, and is adapted to be removed by the usual operation of trimming the inseam of a welted shoe.

Of the accompanying drawings forming a part of this specification: Figure 1 represents a plan view of a shoe upper in a flat condition, embodying my invention; Fig. 2 represents a section on line 2-2 of Fig. 1; Fig. 3 represents a sectional view of a partially completed welted shoe, which includes an upper constructed as shown by Figs. 1 and 2.

40 The same reference characters indicate the same or similar parts in all the views.

Figs. 1 and 2 show an upper in a flat condition before the heel end is closed by the usual seam, said upper as here shown comprising a leather vamp 12 and a leather toe cap 13. 14 represents a relatively narrow strip of tensile fabric which is practically inelastic and inextensible and has a substantial degree of tensile strength so that it is adapted to withstand a strain exerted on and through it for the purpose of pulling the upper over upon the last. The strip 14 is composed of a fabric which may be called tape, the warp threads extending lengthwise of the strip and the weft

threads crosswise and at right angles to the warp threads, the strip being woven with selvage edges, which are of equal or uniform length each edge having the same length as the opposite edge. The inner edge portion is attached to the outer edge portion of the upper by stitches 15, the strip being coextensive in length with the edge of the upper to which it is attached.

As indicated by Fig. 1, the strip 14 projects outwardly from the edge of the upper, and increases the area of the upper as prepared for lasting, the width of the projecting portion of the strip being such that said portion is adapted to be grasped by the usual pulling-over instrumentalities, which therefore do not necessarily directly engage the leather of the upper.

After the strip 14 has been utilized in pulling over the upper, and the upper, when the shoe is of welted construction, has been secured by the usual inseam stitches 17 to the inner sole 18 and welt 19 (Fig. 3), the projecting portion of the strip 14 may be readily cut away by the usual inseam trimming instrumentalities, the leather portion of the upper being of such area that its edge requires little or no trimming.

The inextensibility of the strip 14 and the parallelism and uniformity in length of its selvage edges cause the outer edge portion of the strip to curl or be deflected laterally at the toe portion of the upper when its inner edge portion is stitched to the upper. Said curled or deflected portion forms a lip or flange 14^a which projects from one side of the toe portion of the upper, as shown by Fig. 2, and is adapted to be accurately and conveniently grasped by the pulling-over instrumentalities in lasting the toe portion, said lip being relatively free from folds or wrinkles, because it conforms approximately to the outer surface of the toe portion of the inner sole.

When the upper is closed at its heel end by the usual heel seam and its lower edge portion is bent over the bottom of the last, the heel portion of the strip forms a lip or flange adapted to conform approximately to the outer side of the heel portion of the inner sole. This portion of the strip is not removed by the operation of trimming the inseam, and its entire width is utilized as a reinforcing portion which overlaps the heel portion of the inner sole and is attached

thereto by the lasting tacks used in securing the heel portion of the upper to the inner sole, and by some of the nails which attach the heel seat end of the outer sole to the inner sole.

The strip 14, having longitudinal warp threads and weft threads extending crosswise of the strip, at right angles to the warp threads, has all the tensile strength required to resist the strains exerted in pulling over the upper, the warp threads being substantially parallel with the edge of the upper and all of the weft threads being substantially at right angles with said edge, so that the strength of the strip is uniform throughout its entire length and all parts of the strip are adapted to uniformly resist transverse pulling-over strains. The outer selvage edge prevents liability of the fraying and disintegration of the outer edge of the strip, and the inner selvage edge prevents the stitches 15 from tearing through said edge. The uniform direction of the weft threads crosswise of the strip and at right angles with the edge of the upper prevents the strip from stretching crosswise at any point. The selvage edges and the crosswise extending weft threads render the above described reinforcing portion of the strip at the heel end of the shoe very effective and durable, there being no liability of the strip being torn or broken where the tacks and nails pass through it. In other words, the strip is not liable to be pulled outwardly away from the said tacks and nails, by strain tending to cause the latter to tear through the inner edge of the strip.

A relatively narrow strip characterized as above stated has a marked advantage over a lining of substantially inextensible fabric covering the entire inner surface of the upper and of greater area than the upper so that the lower edge of the fabric projects below the upper and forms an extension by which the upper may be pulled over. Such lining is necessarily stitched to the upper along two lines, one at the higher edge and the other at the lower edge of the upper. The intermediate portion of the lining is loose, and if made of relatively thick inextensible fabric is likely to be wrinkled during the lasting operation, thus detracting from the smoothness of the upper. Moreover, said lining cannot have selvage edges, both its upper and its lower edge being necessarily raw, and formed by the operation of cutting the lining from a sheet of fabric. The raw outer or lower edge is liable to be frayed and disintegrated, especially when pulling-over jaws grasp the strip near the raw edge. The projecting

portion of the lining fabric is extensible or liable to stretch at the portions where the warp and weft threads are diagonal or oblique to the edge of the upper. All the weft threads of a lining cut out from a sheet cannot be disposed at right angles to the edge of the upper, and all the warp threads cannot be parallel to such edge.

The fabric of the strip 14 may be treated with rubber cement or other waterproofing material, if desired.

Having described my invention, I claim:

1. A shoe upper comprising a body portion of leather and an edge portion composed of a relatively narrow strip of woven fabric practically inextensible both longitudinally and laterally and stitched to the outer or lower edge of the body portion at its inner edge portion to form a pulling over extension, the longitudinal edges of said strip being of equal length, said strip having weft threads extending crosswise of the strip, and at right angles to the edge of the body portion from which the strip extends, in such manner as to render all parts of the strip of uniform lateral inextensibility.

2. A shoe upper comprising a body portion of leather and an edge portion composed of a relatively narrow strip of woven fabric practically inextensible both longitudinally and laterally, and stitched to the outer or lower edge of the body portion at its inner edge portion to form a pulling-over extension, the longitudinal edges of said strip being of equal length, the outer edge of said extension being deflected inwardly from its inner edge at the curved toe portion of the upper to form a lip adapted to be conveniently grasped by a pulling-over instrumentality in lasting said toe portion, said strip having weft threads extending crosswise of the strip at all parts thereof in such manner as to render all parts of the strip of uniform lateral inextensibility.

3. A shoe upper comprising a body portion of leather and an edge portion composed of a relatively narrow strip of practically inextensible woven fabric of substantially uniform tensile strength at all parts and stitched to the outer or lower edge of the body portion, at its inner edge portion to form a pulling-over extension, said strip having outer and inner selvage edges and weft threads extending crosswise of the strip at all parts thereof.

In testimony whereof I have affixed my signature, in presence of two witnesses.

OSCAR C. DAVIS.
